(57) **CLAIM**

The ornamental design for a medical device inserter, as shown and described.

DESCRIPTION

FIG. 1 is a front perspective view of the medical device inserter showing our new design.

FIG. 2 is a rear perspective view of the medical device inserter of FIG. 1.

FIG. 3 is a front view of the medical device inserter of FIG. 1, the rear view being the same.

FIG. 4 is a left side view of the medical device inserter of FIG. 1, the right side view being the same.

FIG. 5 is a top view of the medical device inserter of FIG. 1; and,

FIG. 6 is a bottom view of the medical device inserter of FIG. 1. Portions of the medical device inserter shown in FIG. 6 forms no part of the claimed design.
